UNITED STATES PATENT OFFICE.

ALFRED M. ZIEGLER, OF BOSTON, MASSACHUSETTS.

DESIGN FOR A GARMENT-GRIP.

SPECIFICATION forming part of Design No. 35,659, dated February 4, 1902.

Application filed October 4, 1901. Serial No. 77,608. Term of patent 14 years.

To all whom it may concern:

Be it known that I, ALFRED M. ZIEGLER, a citizen of the United States, residing at Boston, county of Suffolk, and State of Massachusetts, have invented and produced a new and original Design for a Garment-Grip, of which the following is a specification, reference being had to the accompanying drawing, forming a part hereof.

10 The drawing shows in plan a garment-grip illustrating my design.

The leading or material feature of my design for a garment-grip consists of a one-piece member having at one side an inwardly and downwardly extending opening having the edge of the body part of the grip formed in a concave curve extending to the meeting-point of the adjacent edge of the free end or hook part, the latter being convex and divergent 20 from said concave edge.

The drawing shows a garment-grip A, whose body part a is provided with a slit a¹ at its upper end, a hook a² at its lower end, and an opening a³ at one side, said opening extending inwardly and downwardly and having its 25 inner edge a⁴ convex or curved inwardly from adjacent the slit end of the grip to the bottom a⁵ of the hook and its outer edge a⁶ convex and diverging from the edge a⁴.

I claim—

30 The design for a garment-grip as herein shown and described.

In testimony whereof I have signed my name to this specification in the presence of two subscribing witnesses.

ALFRED M. ZIEGLER.
